UNITED STATES PATENT OFFICE.

ALEXANDER L. HEIZER, OF ANDERSON, INDIANA, ASSIGNOR TO VESTA ACCUMULATOR COMPANY, A CORPORATION OF ILLINOIS.

MAGNETO-ELECTRICAL GENERATOR.

1,135,898.

Specification of Letters Patent.

Patented Apr. 13, 1915.

Application filed April 22, 1909. Serial No. 491,420.

To all whom it may concern:

Be it known that I, ALEXANDER L. HEIZER, of Anderson, county of Madison, and State of Indiana, have invented a certain new and useful Magneto-Electrical Generator; and I do hereby declare that the following is a full, clear, and exact description thereof, reference being had to the accompanying drawings, in which like letters refer to like parts.

10 It is an object of this invention to construct a magneto generator, the frame of which is of an improved construction and in which oscillatable pole pieces are mounted.

15 It is also an object of this invention to provide in combination with a solid integral frame permanent magnets associated therewith and with the pole pieces thereof oscillatably mounted within said frame.

20 The invention (in a preferred form) is illustrated in the drawings and hereinafter more fully described.

In the drawings: Figure 1 is a central vertical section through the magneto. Fig. 2 is a transverse section on line 2—2 of Fig. 1. Fig. 3 is an end elevation of the solid frame with the other portions of the device omitted.

25 As shown in the drawings: The solid frame of the device consists of a base 1, a top wall 2, and integral end members 3 and 4, which are provided with circular apertures therethrough.

30 As clearly shown in Figs. 2 and 3, the bottom wall 1, is of a greater width than the top wall 2, and is provided with ribs 5, projecting vertically and upwardly therefrom, against which the lower ends of an inner series of permanent magnets 6, abut, resting upon the upper surface of said lower base or floor 1. An outer series of magnets 7, is secured closely over said inner magnets 6, and each of said series of magnets interfits between the end walls 3 and 4, of the

35 frame. As clearly shown in Figs. 2 and 3, said respective bottom and top walls 1 and 2, are arched away from one another centrally, and oscillatably mounted in said frame are the respective pole pieces 8 and 9.

40 For this purpose an end cap 10, is secured to said respective pole pieces, and is rotatably mounted within the apertured end wall 4, at one end of the magneto, and at the other end thereof said pole pieces are secured to a cylindrical member 11, also jour-

naled in the apertured end 3, of the frame, and provided with a vertical centrally apertured partition wall 12. Secured upon a threaded circular flange on the cap 10, is a smaller centrally apertured cap 13, and enclosed therewithin is a bearing ring 14, which affords a tracking member or part of a ball race for ball bearings 15. An armature core 16, provided with shaft extensions 17 and 18, respectively, is mounted within the frame of the magneto with the shaft end 17, projecting through the respective caps 10 and 13, and having secured thereon a bearing ring 19, upon which said balls 15, track. At its other end 18, said armature 20 core has two bearings, one in a cap 20, which is secured upon the cylindrical member 11, and the other bearing being formed by a circular grooved ring 21, secured upon the shaft portion 18, and rotating in a ring 22, 25 with balls 23, interposed between said respective rings. Said armature core 16, is provided with oppositely directed arc shaped wing portions 24 and 25, each of which has secured thereto curved plates 26 30 and 27, respectively, the inner half of each of which overlaps a winding 28, upon said core 16.

35 For the purpose of adjusting said pole pieces a ring 29, is rigidly secured upon said cylindrical member 11, and is provided with a handle 30, on the upper side thereof. Integral legs or attaching members 31, are formed integrally upon the under side of the bottom wall or floor 1, of the frame, so 40 that the device when attached in position for use is spaced from the support, whatever it be. The purpose of mounting the pole pieces 8 and 9, oscillatably within the device, is to permit adjustment thereof with 45 adjustment in the timing mechanism, the details of which are not entered into here. The pole pieces, merely being described as oscillatable, show the relation and arrangement of the other parts of the device which 50 form the subject matter of the present invention.

55 The improved arrangement of the parts made possible by the construction thereof affords a device simple in construction and 60 assembly, and of course the operation thereof in producing or generating an electric current is well known.

65 I am aware that various details of construction may be varied through a wide 70

range without departing from the principles of this invention, and I therefore do not purpose limiting the patent granted otherwise than necessitated by the prior art.

5. What I claim as my invention and desire to secure by Letters Patent is:

1. A magneto electrical generator including a solid frame open at the ends and partially open at the sides with upwardly projecting ribs on the base of the frame on each side, pole pieces insertable in said frame, and magnets overlapping the frame and resting upon the base and against said ribs.

10. 2. In a magneto, a frame comprising integral bottom and end walls, said end walls 15 apertured, a top wall integral with the end

walls, and of less width than the bottom wall, said bottom and top wall concaved, ribs integral with the bottom wall having their outer sides in alinement with the edges 20 of the top wall, and permanent magnets having parallel sides to fit tightly against the edges of the top wall and against the outside of the ribs.

In witness whereof I have hereunto affixed 25 my signature in the presence of the witnesses herein named.

ALEXANDER L. HEIZER.
